UNITED STATES PATENT OFFICE.

SEYMOUR DOSS VAN METER, OF DENVER, COLORADO.

DESIGN FOR A BICYCLE-SADDLE.

SPECIFICATION forming part of Design No. 25,588, dated June 2, 1896.

Application filed February 28, 1896. Serial No. 581,205. Term of patent 7 years.

To all whom it may concern:

Be it known that I, SEYMOUR DOSS VAN METER, a citizen of the United States of America, residing at Denver, in the county of Arapahoe and State of Colorado, have invented and produced a new and original Design for Bicycle-Saddletrees; and I do declare the following to be a full, clear, and exact description of the invention, such as will enable others skilled in the art to which it appertains to make and use the same, reference being had to the accompanying drawings, which form a part of this specification.

Figure 1 shows plan view of my design for saddletree. Fig. 2 is a cross-section on the line X X of Fig. 1. Fig. 3 is another cross-section on line Y Y of Fig. 1.

The leading or characteristic feature of my design consists in a rigid metal saddletree for bicycles of general lenticular form, coming

forward in a rounded point and bordered in the rear by an elevated cantle portion of circular outline when seen in plan view, and having in the central portion a longitudinal raised portion extending from front to rear, ²⁵ and provided with two sinuses or depressed portions on either side of said central raised portion and within the circular boundary of the cantle portion of the saddletree. Each sinus is of general pear-shaped form with the ³⁰ apex of the said form directed forward.

What I claim is—

The design for a bicycle-saddletree substantially as herein shown and described.

In testimony whereof I affix my signature ³⁵ in presence of two witnesses.

SEYMOUR DOSS VAN METER.
